UNITED STATES PATENT OFFICE.

OLIVER K. CHANCE, OF MINNEAPOLIS, MINNESOTA.

FLYING-MACHINE.

No. 890,215.

Specification of Letters Patent.

Patented June 9, 1908.

Application filed November 4, 1907. Serial No. 400,482.

To all whom it may concern:

Be it known that I, OLIVER K. CHANCE, a citizen of the United States, residing at Minneapolis, in the county of Hennepin and State of Minnesota, have invented certain new and useful Improvements in Flying-Machines; and I do hereby declare the following to be a full, clear, and exact description of the invention, such as will enable others skilled in the art to which it appertains to make and use the same.

My invention has for its object to provide an improved flying machine, and to this end it consists of the novel devices and combinations of devices hereinafter described and defined in the claims.

The improved flying machine involves both features of the balloon and features of the mechanically propelled aeroplane, and certain of the features of this invention are capable of incorporation in either of these two classes of flying machines, as well as in machines combining the two.

In the accompanying drawings which illustrate the invention, like characters indicate like parts throughout the several views.

Referring to the drawings, Figure 1 is a rear elevation, showing the improved flying machine as an entirety. Fig. 2 is a vertical section taken from front toward the rear through the complete machine, approximately on the line $x^2 x^2$ of Fig. 1, some parts being left in full. Fig. 3 is a horizontal section taken approximately on the line $x^3 x^3$ of Fig. 1; and Fig. 4 is a detail in side elevation, showing in detail a lever-actuated clutch and gear fan-driving mechanism.

The balloon or gas-containing bag is of double convex form and its rim or periphery is maintained in an approximately horizontal plane. The said bag is made up of upper and lower sheets 1 and 2 of oiled silk or other material suitable for holding a confined body of gas, and these, at their edges, are secured with gas-tight joints to a sharp-edged thin metal rim 3 that is approximately V-shaped in cross section and is preferably constructed of aluminum.

A light metal tubular column or mast 4, preferably of aluminum, extends axially through the gas bag and the central portion of the upper sheet 1, is secured with a gas-tight joint to a flanged collar 5 which, in turn, is rigidly secured to the tubular column 4.

Curved umbrella-like metal ribs 6, prefer-

ably of ribbed spring steel, connect the collar or hub 5 to the upper flange of the peripheral rim 3. A tubular collapsible bag 7 surrounds the intermediate portion of the tubular column 4 and at its lower end is secured with a gas-tight joint to the central portion of the lower sheet 2, while at its upper end it is secured with a gas-tight joint to the tubular column 4 at a point close to the upper sheet 1. A multiplicity of oblique guy ropes or wires 8 connect the upper end portion of the tubular mast 4 to the peripheral metallic rim 3 and very greatly assist the ribs 6 in holding said rim 3 in a fixed position in respect to the said mast. In the lower sheet 2 is a normally closed vent cock 9, the purpose of which will hereinafter appear.

At a distance of about ten feet below the inflated bag is a horizontally disposed platform 10, which at its central portion is provided with a longitudinally extended depressed portion 11 that provides the machine with a boat-like body or basket, the greatest length of which is in the direction of the travel of the machine. This platform, in part, is suspended from the metallic peripheral rim 3, by a light metal frame made up, as shown, of corner rods 12, corner brace rods 12' and 13, longitudinally extended tie rods 14 and suitable transverse connections. 85 To the bottom of the platform 10 on opposite sides of the basket 11 are secured brace rods 16 that are so bent that the lower outer portions thereof constitute supporting feet when the machine is rested upon the ground. The 90 lower end of the tubular column 4 is rigidly secured to the platform 10 on opposite sides of the basket 11 by oblique brace bars 17. To the said tubular mast, near its lower end is rigidly secured a transverse bearing bar 18. 95

The numeral 19 indicates a pair of parallel forwardly extended rubber blades that are rigidly secured to upright shafts 20 journaled at their upper ends in the projecting ends of the bearing bars 18, and journaled at their lower ends in suitable bearings 21 rigidly secured to the platform 10. To the lower ends of the rudder shafts 20 are secured worm gears 22 that mesh with worms 23 carried by the ends of a transverse counter-shaft 24 105 mounted in suitable bearings 25 on the platform 10. These worms and worm gears are so arranged that they impart lateral oscillatory movements to the rudder blades 19 and hold the same always parallel. On the 110

shaft 24 is a hand wheel 26 by means of which the said shaft may be rotated in either direction to impart the proper steering movements to the rudder blades in either 5 of two directions transversely of the machine.

Extended vertically through the tubular column 4 and journaled in suitable bearings in the ends thereof and in a bearing 27 secured on the bottom of the basket 11 is a long 10 upright propeller shaft 28. At its upper end, this propeller shaft 28 is provided with a large propeller wheel 29 which is provided with the usual oblique or spiral blades arranged to rotate in a horizontal plane. 15 Near its lower end, the propeller shaft 28 is provided with a bevel gear 30 that meshes with a bevel gear 31, which latter gear, as shown, is driven directly by the shaft of an explosive engine 32, but which, nevertheless, 20 may be driven by a motor of any suitable type.

Mounted to rotate, but held against vertical movements on the upright propeller shaft 28 is a miter gear 33 that is adapted to 25 be connected to the said shaft for rotation therewith by a sliding half-clutch 34 of usual construction, subject to a shipper lever 35 pivotally mounted on the upper end extension of a bearing bracket 36, the diverging 30 legs of which are rigidly secured at their lower ends to the platform 10 on opposite sides of the basket 11. As shown, the lever 35 is adapted to be secured to the bracket 36 in either of two extreme positions by means 35 of a latch segment 37. The miter gear 33 meshes with the miter gear 38 carried by a horizontal forwardly extended counter-shaft 39 mounted in the upper end of the bearing bracket 36, and in the upper end of a similar 40 bearing bracket 40, the legs of which are secured to the platform 10. Secured to the rear end of the counter-shaft 39 is a bevel gear 41.

Axially aligned with the counter-shaft 39 45 is a propeller shaft 42 mounted in the pronged upper end of a bearing bracket 43, the depending legs of which are secured to the front end of the platform 10 on opposite sides of the basket 11. To the rearwardly projecting 50 end of this propeller shaft 42 is secured a propeller wheel 44. At its rear end the propeller shaft 42 is provided with a bevel gear 45 that meshes with a pair of reversely arranged bevel pinions 46 on a transversely ex- 55 tended counter-shaft 47, which counter-shaft, at its intermediate portion, is journaled in a centrally located pedestal 48; and at its ends is journaled in pedestals 49, all of which pedestals are rigidly secured to the 60 platform 10. The bevel gear 41 of the counter-shaft 39 meshes with a bevel gear 50 secured to the counter-shaft 47, so that the latter counter-shaft will be continuously driven from the former.

65 In the pronged upper end of each bracket

49 is journaled a propeller shaft 51 provided at its rearwardly projecting end with a propeller wheel 52, and provided at its rear end with a bevel gear 53. The two laterally spaced propeller shafts 51 are parallel to the 70 centrally located propeller shaft 42. The bevel gears 53 each mesh with a pair of reversely arranged bevel gears 54 rotatively mounted but held against sliding movements on the transverse counter-shaft 47. 75

For coöperation with each of the three pairs of loose reversely arranged bevel gears 54—46 and 54, there is provided a sliding clutch sleeve 55 that is connected for rotation with, but free for sliding movements on 80 said counter-shaft 47, and is provided with clutch teeth at its opposite ends adapted for engagement with half clutches carried by the coöperating loose bevel gears upon which the said sleeve works. For this construction see particularly Fig. 4, but also note Figs. 2 and 3. Each of these clutch sleeves 85 55 are subject to a shipper lever 56 that is adapted to be held in either of three positions by a latch segment 57 shown as secured to the support to which the coöperating lever is pivoted. The centrally located lever 56, which actuates the sleeve that co- 90 operates with the loose pinions 46, is pivoted to the supporting bracket 40 (see Fig. 2), 95 while the outside levers 56 are pivoted to projections of the bearing columns 49 (see particularly Fig. 1) and are provided with inwardly projecting operating rods 58 that terminate in hand-pieces located within 100 reach of a person within the basket 11.

Deflecting wings or leaves 59 are hinged to the front and rear edges of the platform 10 being, as shown, connected thereto by hinges 60. Transversely extended rods 61 105 that are concentric to the joints of the hinges 60 are rigidly secured to the respective deflecting leaves 59, as shown, by bearings 62. On each hinge rod 61 is a small worm gear 63 that meshes with a worm 64. 110 The two worms 64 are secured to the opposite ends of a shaft 65 mounted in suitable bearings 66 secured to the front and rear portions of the basket 11. One of the worms 64 has right and the other has left 115 threads, so that when the shaft 65 is rotated in one direction the two deflecting leaves will be simultaneously raised, and when the said shaft is rotated in the other direction the said two leaves will be simultaneously 120 lowered. At its intermediate portion, the shaft 65 is provided with a hand-wheel 67 by means of which it may be rotated in either direction to accomplish the above noted adjustments of the deflecting leaves 59. 125

The numeral 68 indicates a gas genera or that is connected by means of a valved pipe or tube 69 to the interior of the gas bag 1—2. This gas generator is intended simply to afford a supplemental supply of gas to replen- 130

ish the gas supply within the bag during flight, or when the machine requires gas when away from the main source of supply.

Suitably mounted on the frame-work and, as shown, mounted directly on the transverse rods 15 are spring rolled curtains 70, which are much like ordinary automatically wound window shades, but are larger and stronger. These curtains are capable of being independently pulled down by ropes or cords 71 which, as shown, run over guy pulleys 72 on the sides of the platform 10 and are adapted to be suitably secured to the sides of the basket 11.

15 When the wind is blowing hard in a direction from the right toward the left in respect to Fig. 1, for example, its friction upon the inflated bag will tend to rock the top of the machine toward the left, and to offset this the left hand curtain should be drawn down more or less, so that it will act much as a sail, and the force of the wind upon the curtain at a point below the bag will compensate for the rocking tendency above noted and tend to maintain the machine in an upright position.

As is evident, the entire machine may be made to rise by one movement of the upper propeller 29 and may be caused to lower by a reverse movement of the said propeller. The upward and downward movements of the machine when in flight may be also largely controlled by adjustments of the so-called deflecting leaves or wings 59. When the said deflecting leaves or wings are moved upward they tend to cause the machine to rise, and when moved downward they tend to cause the machine to lower. When they are in a horizontal plane, as shown in Fig. 2, they tend to maintain the machine at a constant altitude. The machine is given its traveling movements by means of the propellers 52-44 and 52. When said propellers are rotated in the one direction, forward motion will be imparted to the machine, and when they are rotated in a reverse direction, a rearward motion will be imparted to the machine. The machine is guided by the rudder blades 19. With the construction shown, reversal of the engine 32 is required to reverse the direction of the rotation of the upper propeller 29, but shifting devices similar to those used in connection with the other propellers might be employed. As is evident, all three of the propellers 52-44-52 may be simultaneously thrown into and out of action by manipulations of the shipper lever 35 and sliding clutch 34. By movements of the shipper levers 56 and co-operating clutches and gears, the said propellers 52-44 and 52 may be coupled to the transverse counter-shaft 47 for rotation in either direction.

If, by accident, the gas bag should be punctured and the gas leaked therefrom, the

lower sheet 2 thereof will be pressed upward against the upper sheet 1; and in view of the arched shape of the supporting frame for the upper sheet, the deflated bag or balloon will act as a parachute to prevent dangerously rapid descent of the machine. It will also be noted that the inflated bag is of such shape that it will travel through the air in an approximately horizontal direction under a minimum of resistance.

70 Preferably the machine is caused to travel forward with the rudder blades 19 projecting ahead and with the three propellers 52-44-52 located at the rear of the machine. By manipulation of the laterally spaced propellers 52 which are located one on each side of the longitudinal center of the machine, the direction of travel of the machine may be controlled. By running one of the said propellers 52 in one direction and 85 the other in an opposite direction, the machine may be caused to turn in either direction very abruptly.

What I claim is:

1. In a flying machine, the combination 90 with an arched skeleton frame including curved metal ribs and an annular rim secured to the outer ends of said ribs, which rim is approximately V-shaped in cross section, of upper and lower bag-forming sheets attached 95 to said annular rim, and a support located below said bag and suspended from said annular rim, substantially as described.

2. In a flying machine, the combination 100 with an arched skeleton frame comprising curved ribs and an annular metal rim, of a tubular column extending vertically through said bag and secured to the inner ends of said ribs, guy rods or connections between said annular rim and the upper end of said tubular 105 column, a propeller shaft extending through said tubular column and provided at its upper end with a propeller, a support located below said bag and suspended from said annular rim, an approximately horizontal propeller shaft carried by said support and provided with a propeller, a rudder-blade carried by said support, and a motor carried by said support and having connections to said propeller shafts for rotating the same, substantially 110 as described.

3. In a flying machine, the combination 120 with an arched skeleton frame comprising curved ribs and an annular metal rim that is approximately V-shaped in cross section, of a gas bag having upper and lower sheets connected to said annular rim, a tubular column extended through said bag and connected to the inner ends of said ribs, said bag having a collapsible tube 7 secured to said tubular 125 column near the top of the bag, a propeller shaft extended through said tubular column and provided with a propeller at its upper end, a platform located below and suspended from said annular rim and from said tubular 130

4
column, horizontal propeller shafts carried by said platform and provided with propellers, a pair of rudders carried by said platform and connected for parallel swinging movements, a motor carried by said platform and having driving connections to said propeller shafts, deflecting wings pivotally connected to the front and rear edges of said platform, and means for imparting simultaneous

upward and downward pivotal movements ¹⁰ to said deflecting wings, substantially as described.

In testimony whereof I affix my signature in presence of two witnesses.

OLIVER K. CHANCE.
